[57] CLAIM

The ornamental design for a combined wristwatch and
bracelet, as shown and described.

DESCRIPTION

FIG. 1 is an extended top plan view of a combined
wristwatch and bracelet showing my new design;
FIG. 2 is an extended bottom plan view thereof with the
clasp ends turned 90°;

FIG. 3 is a front elevational view thereof in a curved,
wrist-confirming position;

FIG. 4 is a rear elevational view of FIG. 3;

FIG. 5 is a left side elevational view of FIG. 3; and

FIG. 6 is a right side elevational view of FIG. 3.

FIG. 1

FIG. 2

FIG. 3

FIG. 4
